UNITED STATES PATENT OFFICE.

FRANK H. WARREN, OF LYNN, ASSIGNOR TO GEORGE H. P. FLAGG, OF BOSTON, MASSACHUSETTS.

CUTTER-GUARD.

SPECIFICATION forming part of Letters Patent No. 514,741, dated February 13, 1894.

Application filed September 30, 1893. Serial No. 486,867. (No model.)

To all whom it may concern:

Be it known that I, FRANK H. WARREN, of Lynn, in the county of Essex and State of Massachusetts, have invented certain new and useful Improvements in Cutter-Guards, of which the following is a specification.

This invention has for its object to provide a guard adapted to cover the acting portion of a rotary cutter, such as is used for trimming parts of boots and shoes, for the purpose of preventing injury to the article to be trimmed while said article is being presented to the cutter.

The invention is particularly intended for use in connection with inseam-trimming machines, of the character shown in Letters Patent of the United States No. 456,041, dated July 14, 1891, and No. 488,591, dated December 27, 1892. The machine shown in said 20 patents comprises a rotary cutter adapted to trim the upwardly-turned edges of the welt and upper of a welted boot or shoe. In the practical operation of said machine, it has been found that there is more or less liability 25 of contact of the article to be trimmed, which I shall hereinafter call the work, with the cutter, before the work is in its proper position relatively to the cutter, so that there is liability of the work being injured by improper presentation to the cutter.

My invention prevents this liability, and consists mainly in the combination with a rotary cutter of a guard, movable in the arc of a circle over the perimeter of the cutter and 35 normally held in position to cover the acting portion of the cutter; a slide movable on a fixed guide and provided with a rest which is located near the cutter, and occupies such position that the work, in being presented to 40 the cutter, first bears on said projection and necessarily displaces the latter before it can come in contact with the cutter; and intermediate mechanism, connecting the said slide with the guard, whereby displacement of the 45 slide by the contact of the work with it will cause a displacement of the guard, so that, just as the work reaches a position to receive the action of the cutter, the guard is withdrawn and exposes the acting portion of the 50 cutter.

The invention also consists in certain me-

chanical contrivances incidental to the general purposes above mentioned.

Of the accompanying drawings, forming part of this specification: Figure 1 represents a front elevation of a portion of an inseam-trimming machine, provided with my improvements, the guard being shown in its normal position, covering the acting portion of the cutter. Fig. 2 represents a side elevation, 60 the guard being in the same position as shown in Fig. 1. Fig. 3 represents a view similar to Fig. 2, showing the rest and the guard displaced by the work. Fig. 4 represents a section on line 4-4 of Fig. 1.

The same letters of reference indicate the same parts in all the figures.

In the drawings: A represents the shaft, which supports the rotary cutter E and the feed-wheel N; and D represents the yielding- 70 ly-supported disk, which maintains the welt of a boot or shoe in engagement with the feed-wheel; said parts being arranged as fully set forth in the above-mentioned Letters Patent.

a represents the guard, which as here 75 shown, is composed of a curved plate, formed to partially encircle the perimeter of the cutter and to cover the lower or acting portion thereof in such manner as to prevent the work from touching the cutter when the guard 80 is in its normal position.

The guard is affixed to a segmental plate or carrier a', formed on a collar a², which is fitted to turn loosely on a sleeve a³ affixed to the feed-roll N. The guard a is therefore 85 adapted to move in a circular path, which is preferably concentric with the axis of the cutter.

The guard may be normally held in the position shown in Figs. 1 and 2 by any suitable 90 means. I have here shown a spring b, adapted to accomplish this purpose, said spring acting on the guard through mechanism hereinafter described, although it may be otherwise arranged to act directly on the guard, 95 the essential thing being the yielding maintenance of the guard in its normal position, and its return to said position when the force applied to remove it therefrom is discontinued.

c represents a movable projection or rest, which is yieldingly supported in a position

adjacent to the cutter and projecting somewhat below the same, the arrangement being such that the work, in being presented to the cutter, will bear on the rest before it reaches the cutter, and will necessarily displace the rest before it comes in contact with the cutter. The rest, as here shown, is composed of a roll, journaled on a slide c' , which is fitted to move vertically in guides formed on a bracket F affixed to the frame of the machine, said slide being here shown as connected with said bracket by means of screws c^2 c^3 , passing through slots c^6 c^7 in the slide. The spring b above mentioned is attached at one end to the bracket F , and at its other end to the slide c' .

The slide c' is connected with the guard-carrier a' by the following devices: e represents a lever, pivoted at e' to the bracket F , and engaged at one end with the slide c by means of a pin e^2 , passing through a slot e^3 in said lever, and secured to an arm on the slide c' . f represents a rod, connecting the other end of the lever e with a pin or stud f' on the carrier a' .

It will be seen that the spring b presses downwardly on the slide c' , thus holding the same, together with the roll c , depressed as far as the screws c^2 and slots c^3 will permit, the arrangement being such that the roll c is held below the lower portion of the cutter, as shown in Figs. 1 and 2.

When the work is being moved upwardly toward the cutter, it first comes in contact with the roll c , pressing the latter and the slide c' upwardly, and thus causing the intermediate parts e f to move the guard-carrier and guard in the direction required to withdraw the guard from under the acting portion of the cutter, so that, by the time the work reaches the cutter, the guard is removed from the acting portion thereof, as shown in Fig. 3. All liability of injuring the work by the cutter during the presentation of the work to the cutter is therefore obviated.

The bracket F is used, as shown in the above-mentioned Patent No. 488,591, to guide a vertically-movable spindle G , which is intended to impart a downward movement to the roll c when the operator desires to decrease the depth of the cut in the upwardly-turned edges of the work, a lever I being provided, which may be operated by a treadle, as shown in the last-mentioned patent, to press downwardly on the spindle G and thus depress the roll or rest c . In the Patent No. 488,591, the roll or rest was shown connected directly to the spindle G ; but in the present instance, it being necessary to give the roll or rest the described guard-displacing movement before beginning the cutting operation, the slide that supports the roll c is made independent of the spindle G .

To enable the roll or rest to be depressed by the operator, for the purpose of varying the depth of cut, as described in Patent No. 488,591, I provide the spindle with a shoulder

j , and the slide c' with a corresponding shoulder j' , said shoulders being arranged so that, when the spindle is depressed by the act of the operator, the shoulder j will strike the shoulder j' and thus depress the roll or rest c and cause the depression of the work, in the manner described in the said Patent No. 488,591. The depression of the slide c' and roll or rest c accomplished for this purpose is very slight, and is not sufficient to move the guard into position to cover the acting part of the cutter, the guard being in its displaced or raised position when the operator exerts downward pressure on the spindle G to vary the depth of the cut. A spring j^5 is provided, as shown in said patent, to normally raise the spindle G , so that the shoulders j and j' are normally separated, as shown in Fig. 2. 85

I do not limit myself to the described details of construction or to the particular intermediate mechanism used for connecting the rest or projection c with the cutter guard, as I desire to include within the scope of my invention any construction and arrangement of parts which includes a guard movable in the arc of a circle over the perimeter of a rotary cutter, a slide movable on a fixed guide adjacent to the cutter and a rest on said slide normally held in position to bear upon the work before the latter reaches the cutter, the arrangement being such that movement imparted by the work to the rest is caused to impart to the guard a movement away from the cutter while the work is approaching the latter.

My invention is not limited to use in connection with the cutter of an inseam-trimming machine, and may be adapted to rotary cutters for various other purposes without departing from the spirit of the invention.

The spindle G is adjustable vertically by means of nuts G^2 G^3 G^4 , as shown in the last-mentioned patent, so that the shoulder j may be raised or lowered to vary the height of the rest c when the latter is raised to its highest position, the object of such variation being to make the maximum depth of cut greater or less. 115

As any adjustment of the spindle G would vary the distance between the shoulders j j' and the throw of the guard, without a corresponding adjustment of the slide c' , I provide means whereby the slide may be adjusted without changing the positions of the connecting devices e f , said means comprising a plate c' , adjustably secured to the slide c' by screws c^6 c^7 passing through slots c^6 c^7 in said plate, the plate being connected with the lever e . By loosening the screws c^6 , I am enabled to adjust the slide and the roll c up or down, and thus compensate for any adjustment of the spindle G . 125

I claim—

1. The combination with a rotary cutter, of a guard movable in the arc of a circle over the perimeter of the cutter and normally held in position to cover the acting portion of the

5 cutter, a rest-carrying slide movable on a fixed guide and adapted to be moved by the pressure of the work against it, said rest being adjacent to the cutter, and intermediate connections between said guard and slide, whereby a movement of the rest and slide is caused to displace the guard and expose the cutter.

10 2. The combination with a rotary cutter, of a guard movable in the arc of a circle over the perimeter of the cutter and yieldingly held in position to cover the acting portion of the cutter, a rest-carrying slide movable on a fixed guide and yieldingly supported in position for the rest to come in contact with the work before the latter comes in contact with the cutter, the rest being adapted to be displaced by a movement of the work toward the cutter, and connections between the slide and guard whereby movement is imparted from rest and 15 slide to the guard, as set forth.

20 3. The combination with a rotary cutter, of a movable guard mounted to move in the arc of a circle over the cutter, a yieldingly-supported slide movable on a fixed guide and having a rest which normally projects below the acting portion of the cutter so that the work in being presented to the cutter will first strike the rest and displace the same, and connections between the slide and guard whereby 25 the guard is displaced with the rest and slide, as set forth.

30 4. The combination of a rotary cutter, a movable guard mounted to move in the arc of a circle over the cutter, a slide movable on a

fixed guide and provided with a rest *c*, connections between the slide and guard, and a spring which yieldingly holds the slide, rest, and guard in their normal positions, as set forth.

35 5. The combination of a rotary cutter, a guard movable in the arc of a circle and mounted to oscillate over the cutter, a rest or projection, such as *c*, a slide supporting said rest, a fixed guide for said slide, connections between the slide and guard, a vertically-movable spring-supported spindle or rod adapted to be depressed into contact with the slide and to depress the latter, and a spring which yieldingly holds the slide, rest, and guard in their 40 normal positions, as set forth.

45 6. The combination of a rotary cutter, a movable guard mounted to oscillate over the cutter, a slide having a rest, such as *c*, connections including a lever *e* between the slide and guard, means for adjusting the slide vertically with relation to said lever, a vertically-movable spring-supported spindle or rod adapted to be depressed into contact with the slide, and means for vertically adjusting said 50 spindle, as set forth.

55 In testimony whereof I have signed my name to this specification, in the presence of two subscribing witnesses, this 21st day of September, A. D. 1893.

60 FRANK H. WARREN.
